DESIGN FOR A SCABBARD FOR A UNIVERSAL COMBAT KNIFE

Taylor E. Huff, Fort Knox, Ky.

Application February 28, 1944, Serial No. 112,743

Term of patent 7 years

(Cl. D22—6)

To all whom it may concern:

Be it known that I, Taylor E. Huff, a citizen of the United States of America, residing at Fort Knox, county of Hardin and State of Kentucky, have invented a new, original, and ornamental Design for a Scabbard for a Universal Combat Knife, of which the following is a specification, reference being had to the accompanying drawing, forming a part thereof wherein:

I claim:

The ornamental design for a scabbard for a universal combat knife, as shown.

TAYLOR E. HUFF.
